Des. 183,856
Patented Nov. 4, 1958

183,856

COMBINED COIN HOLDER AND BILL CONTAINER

Jesse H. Moses, Chicago, Ill., assignor to Herring-Hall-Marvin Safe Company, Hamilton, Ohio, a corporation of Ohio

Application December 2, 1957, Serial No. 48,742

Term of patent 14 years

(Cl. D52—4)

FIG. 1

FIG. 2

I claim:

The ornamental design for a combined coin holder and bill container, as shown.
